AUTOMATIC CONTROL MECHANISM FOR
FOLDING MACHINES

Leo M. Kahn, New York, N. Y., assignor, by
mesne assignments, to American Laundry
Machinery Company, Cincinnati, Ohio, a cor-
poration of Ohio

Application January 9, 1931, Serial No. 507,556

9 Claims. (Cl. 270—61)

This invention relates to folding machines and more particularly to the automatic control mechanism therefor.

Among the objects of the invention are:

5 To provide for automatically folding articles of various sizes in predetermined ratio proportional to their lengths; 60

To provide for automatically selecting the ratio of fold division;

10 To include the measuring device and electrical control mechanism in a unit that will control the actuation of the folding devices remotely therefrom;

To effect the measurement and the selection 15 of the ratio of fold of the articles prior to the disposition of the article in operative relation to the folder;

To effect the measurement and the selection 20 of the ratio of fold of the articles by means of a plurality of riders travelling with members at fractional rates of speed relative to that of the moving article.

These and other objects are attained by a control device described in the specification and illustrated in the drawings forming part thereof, the novel improvements being specifically set forth in the claims.

In the drawings,

Fig. 1 is a side elevation of the control device 30 with parts removed.

Fig. 2 is a sectional elevation of the control device, viewed along line 2—2 in Fig. 1.

Fig. 3 is a sectional elevation of the control device viewed along line 3—3 in Fig. 1.

35 Fig. 4 is a fragmentary plan view of the portion of control device shown in Fig. 3.

Fig. 5 represents a detail of the rider.

Figs. 6 and 7 represent details of cams.

Fig. 8 is a schematic representation of a folding machine embodying the invention showing the 40 electric circuit diagram.

Fig. 9 shows a typical form of the contact switch mechanism in the folding machine, as adapted to this invention.

45 Fig. 10 is a detail of a switch dog, slidably mounted on the inner contact arm of one class of the riders.

Fig. 11 is a cross sectional view thereof.

Fig. 12 is a top view thereof, illustrating also 50 the section of cam cooperating with it.

Figs. 13 and 14 are diagrams illustrating the active and inactive zones of two different combinations of measuring sheaves.

In a type of folding machine schematically represented in Fig. 8, a frame A has mounted there-

on a system of rollers B which are suitably driven and thereby cause the tapes C to move over them. Articles D are adapted to be fed from table E and to be frictionally conveyed by the tapes C toward folding devices F, F' and thence to delivery tables G.

Near the feeding end, disposed between the tapes C in the path of the articles D are switches 11 which are resiliently mounted and are adapted to be depressed by the articles D while same 65 pass over them. Upon depression, switch 11 makes electrical contact with terminal 12 and thereby closes the circuit which energizes solenoids 13 and 14 remotely mounted in control box

15. Upon release of switch 11, spring 16 mounted on slide rod 17 as best shown in Fig. 9, causes the pivotally mounted lug 18 to actuate and immediately release switch 19 as the lug 18 moves back with the rod 17. Actuation of switch 19 causes same to contact terminal 20 and thereby 70 closes the circuit which energizes solenoids 21 and 22 also mounted in control box 15, see Fig. 8. 75

The control box 15 is preferably mounted on the base of the frame A and shaft 23 mounted within the box and extending outside thereof is driven by means of chain drive 24 operatively connected to the same driving means as rollers B. The box 15 is also separately represented in the electrical diagram in Fig. 8 and Figs. 1, 2 and 3 show the contents thereof to an enlarged 80 scale. Keyed to the shaft 23 is gear 25 which meshes with gear 26 and thereby drives shaft 27 to which it is keyed, and the gears 28 and 29 which are likewise keyed to the shaft 27 as is best shown in Fig. 1. It is preferred that shafts 23 and 27 rotate at the same speed, the sheave 30 rotating with the shaft 23 to which it is keyed. 85

Sheaves 31 and 32 are keyed to tubular shafts 33 and 34 respectively which are concentrically mounted on shaft 23 and are driven by means of gears 35 and 36 which mesh with gears 28 and 29 respectively. The gear ratios of gears 35 to 28 and 36 to 29 are preferably greater than one and each of the different value, so that sheave 31 rotates at say two thirds the speed of sheave 30 and sheave 32 rotates at say one half that speed. 90 95 100

Loosely mounted on shaft 23 between the sheaves 30 and 31 are a plurality of members 37, and between sheaves 30 and 32 are 105 similar members 38 likewise mounted. Each of these members 37 and 38 have pivotally mounted thereon and successively aligned in one plane the riders 39 and 40 respectively, of which riders 39 are adapted to frictionally 110

engage either of sheaves 30 or 31, while the riders 40 are adapted to engage sheaves 30 or 32, and rotate with them at their respective speeds. At one extremity of each rider 39, 5 40 is a spring 41 which tends to hold the rider frictionally in contact with sheave 30.

At the other extremity of each of the riders is a roller 42 which is normally held in an outward disposition relative to the shaft 23 by virtue 10 of the action of the spring 41. The progress of these rollers and the deflection of their course is a radial direction by various mechanical means, as explained hereafter, has been indicated on Fig. 2 by small dotted circles. Each of 15 said riders 39 and 40 also has a slidably mounted projection piece 43 adapted to be moved approximately perpendicularly to the plane of rotation of the riders. As Figs. 1 and 5 indicate, this piece, formed like an inverted T and slidably in 20 a double fork, can, either when the rider is travelling in a straight course, or while in act of tilting over from one speed-wheel to the other, be shifted into or out of the line of operative action by cams provided for this purpose and 25 described later. A little friction disk 80 of soft rubber, provided over one of the sliding arms, prevents spontaneous dislocation, once the piece is shifted into one or the other position. When 30 actuated by the momentary action of the plungers of solenoids 13 and 14, the rollers 42 are depressed to a lesser distance from shaft 23 than the deflecting guides 44 and 45, being formed as 35 circular flanged disk segments and causing the riders to pivot about the members 37 and 38 respectively and the contact portions 46, 47 of the 40 riders 39 and 40 respectively to be brought to bear against sheaves 31 and 32. Thus the riders are made to travel with sheaves 31 and 32 instead of with sheave 30, so long as rollers 42 are held within the confines of the guides 44 and 45 respectively.

When solenoids 21 and 22 are momentarily energized by the release of switch 11 by the rear edge of the article, they draw the guides 44 and 45 respectively away from the corresponding sheaves 31 and 32, springs 48, 49 restoring the guides to normal position. Thereupon the riders are restored to contact with sheave 30 with which they then travel.

50 The zoning of the articles and selection of the line of fold at the center or two thirds mark is effected by deflecting guides 50 and 51 in the path of riders 39 and guides 73 and 52 in the path of riders 40 see Fig. 2. These guides are 55 adapted to deflect the slidable projection piece 43 into or out of the plane of the switches 53, 54 respectively, the aligned rider thereupon actuating the corresponding switch to contact the terminal 53', 54'. Actuation of either of these 60 switches closes the electromagnet 55 circuit, Fig. 8, and thereupon draws armature 56 to the contacts 57, which effect energization of the solenoid 58 and consequent actuation of the folder wedge 59 of folder F. The article is thereby drawn up 65 between the rollers 60 along the desired line of fold and proceeds toward the next folder F'.

The control device also zones articles into the 70 number of folds as well as selects the ratio of fold division. To that end, a switch 61, Fig. 2, is adapted to be actuated by a slidably mounted projection 62 on the extension 63 of rider 40. See Figs. 2 and 10. If the rider continues on the half speed wheel when passing cam 64, the 75 projection 62 is moved by the cam 64 so that when the rider reaches switch 61 it will actuate

same and close the circuit including solenoid 65. A feather 81 prevents premature spontaneous dislocation of the shifted projection, similar to the function of the rubber disk 80.

Upon becoming energized solenoid 65 draws in 80 plunger 66 and stop member 67 actuated by the spring 67' is shoved into the path of the riders 40, holding same until the article had been folded and had progressed toward point 0'. When the leading edge of the folded article actuates switch 11' which is a duplicate of switch 11, solenoid 68 is energized and its plunger forces the solenoid 65 axially toward the shaft 23.

Thereby stop member 67 is brought back into 90 its original position with simultaneous compression of spring 67' and reengagement with plunger 66, so that when solenoid 68 is released, stop member 67 will be drawn back out of the way of the riders 40. By the forward movement of solenoid support 65, as aforesaid, the roller 42 is 95 forced underneath the guide 69. This guide is similarly shaped to the afore-mentioned segmental circular guide 45. The rider 40 is the only one actuated thereby in the construction shown for effecting a center fold, and being thus 100 frictionally engaged to wheel 32, travels with the wheel at half the speed of the article until the rear edge of same releases switch 11' and thereby causes actuation of switch 19' and consequent energization of solenoid 70. Guide 69 is 105 thereupon drawn back so that rider 40 resumes contact with the full speed wheel 30, travelling with same until projection 43 strikes switch 71 and thereby causes actuation of the folding device F' see wiring diagram of Fig. 8 and left 110 side of Fig. 2. As the rider continues its movement, projections 43 and 62 are realigned by cam 72 and cam 77 respectively, and the riders 39 and 40 line up at the rear of the riders, ready to be actuated again by the plunger of solenoids 13 115 and 14. This lining up of the riders and coming to rest is facilitated by the circular segmental guides 74 which are located in the path of the rollers 42, right in front of the solenoids 13 and 14 and gradually depress the rollers so that the 120 contact arms on the wheel 30 are lifted off the same.

The operation of the device is evident from the above description of the coordinating parts, but will be outlined here as follows:

125 As articles of various sizes are fed into the machine, the leading edge of each actuates switch 11 which stays down until the rear edge releases it, i. e. for the full length of each article. During that interval a rider 39 is caused 130 to travel with wheel 31 at say two-thirds the speed of the article, and a rider 40 simultaneously travels at say one half that speed while the circumferential speed of sheave 30 corresponds to the speed of the article itself.

135 Thus, for the full length of each article, one rider reaches a point two-thirds the length of the article while another rider is at the center relative to the length of that article. This becomes more apparent by a comparison of diagram Fig. 13 with Figs. 2 and 3. Upon release of switch 11, solenoids 13 and 14 are deenergized and solenoids 21 and 22 are momentarily energized, so that by virtue of the temporary removal of the stationary guides, riders 39 and 40 are 140 released from engagement with the wheels 31 and 32 respectively and travel with the full speed wheel 30.

145 Assume the sizes of articles are divided into zones, say as follows:

(a) Articles up to 10 inches long to pass unfolded.

(b) Articles between 10 and 20 inches long to receive one fold at center.

5 (c) Articles between 20 and 34 inches long to be folded into three equal parts, viz. one-third from one edge and then at center.

(d) Articles longer than 34 inches to be folded in half and again in half.

10 All riders, when released by plunger action of solenoids 13 and 14, have their projections 43 in operative position that is: adapted to strike and operate switches 53 and 54 respectively, which control the folding mechanism at F, but in case (a) projections 43 on riders 39 as well as on 40 are deflected by cams 73 and 50 respectively and therefore made inactive. No fold consequently is effected. In case (b), projection 43 on rider 39 is deflected by cam 50 and thereby made inactive. But when rider 40 reaches switch 54, corresponding to the alignment of the center line of the article with folder F, it actuates the switch and causes kickup 59 to fold the article. Projection 62 on the rider 25 being kept normally in the inactive disposition, does not actuate switch 61, so that the rider continues on the wheel 30. After passing the solenoid 68 the projection 43 of this rider is caused to be deflected by cam 76 when in engagement with wheel 30, so that it does not actuate switch 30 71 and hence the article passes on with only one center fold.

In case (c) projection 43 on rider 40 is deflected by the cam 53, so that switch 53 is actuated by rider 39, while rider 40 passes by switch 35 54, whereby the article is folded when only one third of its length had passed the folder F. Also, projection 62 on rider 40 has been deflected by cam 64, so that when it passes switch 61 controlling solenoid 65 it actuates same and causes stop member 67 to come up by virtue of the energization of solenoid 65. When switch 11' is thereafter actuated by the leading edge of the folded article, solenoid 68 is energized and the 40 rider 40 is caused to engage the half speed wheel 32 until switch 11' is released. Projection 43, which was made inoperative by cam 52, is brought back into an operative position by cam 75 simultaneously with the transfer of the rider to the 50 half speed wheel and, thus brought into alignment with switch 71, it thereby causes the folder F' to be actuated when the center of the article has aligned therewith.

In case (d) projection 43 of rider 39 is deflected by cam 51 so that it proves inactive, while rider 40 actuates switch 54 for the first center fold. Otherwise the actuations are the same as in case (c).

In all cases where riders are made inactive 60 by the cam 76 or 51, their projections are brought back into an operative position by cams 72 before they have completed their course.

The numerals 10 to 100 and 0' to 50' disposed circumferentially around the sheaves 31 and 32 in Figs. 2 and 3 indicate the progress and location of the riders when travelling in engagement with these wheels, while the front edge of an article which releases these riders reaches the corresponding numeral shown in diagram of Fig. 8. A still more conspicuous idea of this relation may be gained by the diagrams of Fig. 13. The outer ring represents the progress of sheave 30, or the full speed wheel, the middle ring that of sheave 32, the half speed wheel, and

the inner ring that of sheave 31, the $\frac{2}{3}$ speed wheel.

The blackened zones indicate the periods during which the extension members 43 of the respective riders will be in an operative position, in case the riders are transferred from the respective slow speed to the full speed sheaves, so that they can effect a fold. The cross sectioned zones represent the transit of the article from the lower course of tapes "C" to the upper course after the first fold. The points of the first and second fold are also indicated.

Fig. 14 shows a similar diagram for a full, half and $\frac{1}{3}$ speed wheel. In all cases where the third wheel travels slower than the half speed wheel a stop mechanism, as illustrated by solenoid 65, and members 66, 67 is necessary, in other cases it may be dispensed with.

Of course other zoning and fold division could be adopted without departing from the spirit of the invention. It will thus be seen that a device is made available which may be embodied in a remote control unit that will automatically measure articles of various lengths, select the number of folds and ratio of division proportional to the length of the article, make these selections before the actuation of the first fold, actuate the folding devices when the articles are in the desired operative relation thereto, and be automatically available for the next succeeding articles as they are continuously fed into the machine. Regardless of the rapidity of feeding and the number of small or large articles fed in succession, these operations are effected without manual aid.

Of course the details of structure and arrangement of parts might be varied from the disclosure. Moreover, many widely different embodiments of the invention could be made without departing from the scope thereof. It is therefore intended that all matter contained in the description and drawings be interpreted as illustrative and not in a limiting sense.

Accordingly what is claimed and desired to secure by Letters Patent is:

1. In a machine of the class described, including folding means and means for conveying articles thereto, circuit closing contactors in the path of said articles, a measuring and folder actuating device remotely disposed therefrom and including a plurality of riders each adapted to move at lesser and different speeds from that of said articles while same engage said contactors, and in synchronism therewith thereafter, switches in the path of said riders and disposed in coordinated relation to said folding means for actuating same, and means controlled by the lengths of said articles for selecting the actuating riders for said switches to effect the folding when the controlling article is divided by said folding means in the selected ratio of its length.

2. In a device of the class described, including a conveyor and a device for folding flexible articles of various sizes, electrical contactors adapted to be actuated by said articles, and a control device including a plurality of members adapted to move at various speeds in predetermined ratio to that of said articles, a plurality of riders in operative relation to said members, means actuated by said electrical contactors for engaging said riders to one or another of said members whereby to select the ratio of fold division of said articles and means for activating one of said riders to actuate said folding device when said actuating article is divided by said folding device in said selected ratio of its length.

3. In a device of the class described, including a conveyor and a plurality of devices for folding flexible articles of various sizes, electrical contactors adapted to be actuated by said articles, and a control device including a plurality of members adapted to move at various speeds in predetermined ratio to that of said articles, a plurality of riders in operative relation to said members, means actuated by said electrical contactors for engaging said riders to one or another of said members whereby to select the ratio of fold division of said articles, means actuated by one of said riders after measuring a predetermined length of said articles for selecting the number of folds and means for activating the selected riders to successively actuate said folding devices when said actuating article is in the desired operative relation with each of said folding devices.
4. In a device of the class described, including a conveyor of flexible articles of various lengths and a plurality of folding devices, a measuring and actuating device remotely controlled by said articles, and including a plurality of members moving at various speeds in predetermined ratio to that of said articles, a plurality of riders in operative relation to said members, means controlled by said articles for engaging said riders with one or another of said members, electric contactors in the path of said riders, means for deflecting all but one of said riders with respect to said contactors thereby to effect selection of the number of folds and ratio of fold division proportionate to the lengths of said articles and successive actuation of any or all of said folding devices when said contactors are actuated by said riders.
5. In a control device for folding machines for automatically folding articles of various sizes, a plurality of members adapted to move at various speeds in predetermined ratio to that of said articles in their movement toward a device for folding same, a plurality of riders adapted to simultaneously engage one or a plurality of said members, means for coordinating said engagements with the disposition of said articles relative to the folding device to effect measurement of a plurality of divisions fractional of the length of said articles, electrical contactors in the path of said riders, means controlled by the length of said articles for disaligning all but one of said riders, whereby actuation of said contactors will effect the folding of said articles in the selected ratio proportional to its length.
6. In a machine of the class described, including a conveyor and a plurality of devices for folding flexible articles of various sizes, an automatic control device including means for selecting the number of folds to which each of said articles be

subjected, means for selecting the ratio of fold division proportional to the length of said articles and means actuated after actuation of both of said means for actuating said folding devices when said articles had been conveyed into operative relation thereto.

30

7. In a control device, cooperatively connected to a folding machine for automatically folding articles of various lengths, a plurality of members, moving at various speeds in predetermined ratio to that of said articles in their movement toward a device for folding same, a plurality of riders, adapted to engage one or another of said members, means, controlled by the length of said articles for selectively engaging said riders with one or another of said members, electric contactors in the path of said riders, means, controlled by the length of said articles for disaligning all but one of said riders from the path of contact with said contactors, means to automatically delay the progress of any rider travelling further than the one selected for making the contact, until said rider has accomplished the same, and means, whereby the actuation of said contactors will effect the folding of said articles in the selected ratio proportional to the length of the article.

85

8. In a control device, cooperatively connected to a folding machine for automatically folding articles of various sizes a plurality of members, adapted to move at various speeds in predetermined ratio to that of said articles in their movement toward a device for folding same, a plurality of riders, adapted to engage one or the other of said members, means for selectively engaging said riders to said members according to the length of the articles, electric-contactors, in the path of the riders, adapted to actuate the folding means of the folding machine, means to put all riders at the beginning of their course into an operatively engaging position with relation to said electric contactors, means for selectively disaligning any or all of said riders from their contacting path toward said electric contactors, and means to realign all riders at the end of their course into an operatively engaging position.

90

9. In a folding machine, in combination with a conveyor, electric switch members adapted to be actuated by articles carried by said conveyor and a remote control device including a plurality of members adapted to move proportionally to the speed of said actuating articles and cooperative means for selecting the number of folds and ratio of fold division for each fold.
